(57) **CLAIM**

The ornamental design for a clip-on air freshener assembly, as shown and described.

DESCRIPTION

FIG. 1 is a front perspective view of a clip-on air freshener assembly embodying the present invention;

FIG. 2 is a rear perspective view of the assembly, with the attaching clip shown in exploded relationship;

FIG. 3 is a front view of the assembly;

FIG. 4 is a back view of the assembly;

FIG. 5 is a left side view of the assembly;

FIG. 6 is a right side view of the assembly;

FIG. 7 is a top view of the assembly; and,

FIG. 8 is a bottom view of the assembly.
